UNITED STATES PATENT OFFICE.

WILLIAM R. CARROLL, OF PELICAN, LOUISIANA.

STEAM-VALVE.

SPECIFICATION forming part of Letters Patent No. 463,138, dated November 17, 1891.

Application filed June 9, 1891. Serial No. 395,683. (No model.)

To all whom it may concern:

Be it known that I, WILLIAM R. CARROLL, a citizen of the United States, residing at Pelican, De Soto parish, State of Louisiana, have 5 invented certain new and useful Improvements in Steam-Valves, of which the following is a specification.

It is sometimes desirable in operating steam-engines—as, for instance, in operating the engines used for driving cotton-gins—to enable the operator at the gin to cut off the steam from the engine independently of the use of the ordinary throttle; and the object of my invention is to enable this to be done, and I 15 effect this result by combining with the steam-pipe and in addition to the throttle-valve an independent valve and casing, the latter preferably in the form of an elbow, and by arranging connections extending from the said 20 supplemental valve to the gin or other place where the operator is stationed, as fully set forth hereinafter, and as is illustrated in the accompanying drawings, in which—

Figure 1 is a plan view illustrating my improved valve and its connections; Fig. 2, an enlarged sectional view of the valve and casing; Fig. 3, a cross-section on the line 3 3, Fig. 2.

The valve-casing A is preferably made in 30 the form of an elbow with two branches 1 2 for connection with the horizontal and vertical connections of the steam-pipe, so that said casing will constitute a substitute for the elbow which is almost invariably used at some 35 point in the line of the pipe, and in said casing is a partition 4, having an opening 5, with a surrounding face 6, adapted to fit the cylindrical body 7 of a valve B, which body is hollow and provided with an opening or port 40 8, adapted to be brought to coincide with the port 5 of the partition 4, but to be carried wholly from said port when the valve is carried quarter around in each port, the movement of the valve being then limited by the 45 contact of the valve-arm 9 with a stop 10 or 12.

The valve B is hollow and closed at the top and has at the bottom two ports 13 13 and an intermediate cross-piece 14, which, when the valve is turned to carry the port A away from 50 the port 5, comes opposite to and closes an elongated port 15 in a partition 16 of the eas-

ing, so that the ports 5, 8, and 15 will all be opened or closed at the same time.

In order to reduce the friction upon the valve, I cut away the casing, so that the valve 55 will bear only upon the seat 6 around the port 5 and upon two seats at the opposite ends, and I prefer to make these two seats 17 18 tapering or conical, the former adapted to the flaring head 19 of the valve and the latter to the beveled end 20 of the valve, so that the latter may be ground to fit both seats closely, preventing the escape of steam, should any leak around the face 6, and also facilitating the insertion of the valve in the casing. The valve 65 is held in place by means of a spring 21, passing through the cap 22.

A spring or weight is arranged to turn the valve in one direction. For instance, a cord 23, connected with the lever 9, passes over a 70 guide-pulley 24 and has connected to it a weight 25, which tends to pull the lever in the direction of arrow, Fig. 1, to bring it against a stop 10, and thereby close the valve. A cord or other suitable connection 26 extends from the lever 9 to the operator's station at the gin or other position, so that at any time the operator by pulling upon said cord can turn the valve quarter around, closing the ports 5 and 15 and cutting off the 80 steam, regardless of the position of the throttle-valve.

While I prefer to provide the valve with the cross-piece 14 for closing the port 15 for additional security in case of leakage around 85 the case 5, the said cross-piece and port may, if desired, be dispensed with.

It will be seen that the valve above described may be readily constructed, that the only finishing required is at the points 19 20 90 and around the port 8, that the casing A may be readily machined to form the seats in their proper relation, and that said casing serves both as a valve-casing and as an elbow for L-union.

Without limiting myself to the precise construction and arrangement of parts shown and described, I claim—

1. The within-described valve, consisting of a casing having two branches at right angles 100 to each other, a partition 4, provided with a port, inclined valve-seats 17 and 18, and a

hollow cylinder closed at one end and opened at the other, resting on said seats, the cylinder being provided with a port at one side corresponding with the port in the partition, substantially as set forth.

5 2. The within-described valve, consisting of an elbow-casing having two branches, a partition in one of the branches provided with a port 5, and the cylinder V, closed in the valve-casing and having a single side port corresponding with the port 5, the cylinder being provided with a cross-piece 14 at its end corresponding with the ports 15 of the casing, substantially as set forth.

10 15 3. The within-described elbow-valve, consisting of a casing having a partition provided with a single port, ports at the end of the casing, a cylinder fitting the casing and

provided with a single valve in its side corresponding with a valve in the partition and 20 with a cross-piece at its end corresponding to the valve in the case, a cap, a spring between the cap and cylinder, an arm connected to the cylinder and provided with means for turning it automatically in one direction, and 25 a connection leading to a distant point for turning the valve in the other direction from said point, substantially as set forth.

In testimony whereof I have signed my name to this specification in the presence of 30 two subscribing witnesses.

WILLIAM R. CARROLI.
